UNITED STATES PATENT OFFICE

LLOYD Q. SLOCUMB, OF FERGUSON, MISSOURI

RADIO RECEIVING APPARATUS

Application filed March 22, 1924. Serial No. 700,986.

This invention relates to radio receiving apparatus, and with regard to certain more specific features, to apparatus for amateur use.

5 Among the several objects of the invention may be noted the provision of an accurate and simplified control for wave length, and volume; and the provision of a simple and inexpensive device for reducing the distortion of sound in a multi-stage audio amplifier. Other objects will be in part obvious and in part pointed out hereinafter.

The invention accordingly comprises the features of construction, combinations of elements, and arrangements of parts, which are exemplified in the constructions hereinafter described and the scope of the application of which will be indicated in the following claims.

20 In the accompanying drawings, in which is illustrated one of various possible embodiments of this invention,

Fig. 1 is a circuit diagram illustrating applicant's invention;

25 Fig. 2 is a vertical transverse section through the instrument panel, showing a preferred mounting for the variable condenser; and

Fig. 3 is a face view of a coil.

30 Similar reference characters indicate corresponding parts throughout the several views of the drawings.

Referring now more particularly to Fig. 1, there is illustrated a preferred form of wiring.

This diagram is shown adapted for four tubes 1, 3, 5, 7; an aerial 9; a ground 11; an A-battery A; a B-Battery B; and a third battery C.

40 The tubes are preferably of the type ordinarily used for amplification, and known as 201-A.

There are two sets 13, 15 of relatively movable coils. Each set comprises a fixed primary, a fixed secondary or grid coil; and a movable secondary or plate coil.

The set 13 of relatively movable coils comprises a primary 17 of 20 turns of No. 22 double-cotton-covered wire, provided with 50 taps 19 (Fig. 3) at turns 1 to 13 inclusive

and at 16 and 20 turns. This primary coil 17 is connected to ground at 11, and the aerial 9 may be connected to the desired tap. 19 (Fig. 3). The plate coil 21 of this set 13 has 70 to 80 turns of No. 30 double-cotton-covered wire wound on the inside of a fibre spider web frame 23 (Fig. 3); the primary winding 17 is wound on the outside of said spider web 23 and is thus close-coupled to the grid coil 25. The movable or plate coil 21 of the set 13 is of 70 to 80 turns of No. 30 double-cotton-covered wire and is on a separate spider web 27 (Fig. 2). This spider web 27 is pivotally mounted as at 28 so as to be rotatable in a counterclockwise direction (Fig. 2) away from the fixed coils 17, 25 of the set 13. Such movement of the movable coil 21 is effected through a cord 31 secured to the upper end of the movable spider 27 and connected at its other end to the frame plate 33 of the variable condenser 35.

55 This condenser comprises fixed plates 37 and movable plates 39, and is mounted to slide as a whole, in guides 41 secured to the instrument panel 43 by suitable means, such as screws 45 (Fig. 2).

60 Rotation of the knob 47 causes rotation of the movable plates 39 with respect to the fixed plates 37, thereby varying the capacity 65 of the condenser.

65 Longitudinal movement of the knob 47, throughout the range of travel permitted by the slot 49 in the panel 43, causes the condenser to move bodily (vertically in Fig. 2). This bodily movement does not affect the internal capacity of the condenser as an instrument, but is primarily for the purpose of varying the relative position of the coils 17-25 and 21.

70 A tension spring 51 (Fig. 2) tends to hold the spider 27 toward the spider 23. This spring also serves, if necessary, to counter-balance the effect of gravity tending to shift the condenser in a direction to pull the two 75 spiders apart.

75 The grid coil 25 of the set 13 is connected to the grid of the tube 3. The plate coil 21 of this set 13 is connected to the plate of the tube 3.

The other set 15 of relatively movable coils comprises a fixed coil 53 of 8 turns of No. 22 double-cotton-covered wire. The circuit connections of this coil will be described hereinafter. The plate coil 55 of this set 15 comprises 40 turns of No. 30 double-cotton-covered wire, and is connected to the plate of the first or detector tube 1.

The grid coil 57 of the set 15 has 50 turns of No. 24 double-cotton-covered wire, and is connected to the grid of the detector tube 1, through a grid resistance 59 and condenser 61 shunted around said resistance. A variable condenser 63 is shunted around the grid coil 57.

The construction and relative positioning and mode of adjustments of the fixed coil 53, fixed grid coil 57, movable or plate coil 55, and variable condenser 63, of the set 15 is the same as the construction and relative positioning and mode of adjustments of the analogous parts in the set 13, to-wit, the coils 17, 21, 25 and variable condenser 35, respectively.

There are three closed-core transformers 65, 67, 69. Each transformer comprises two windings P and S respectively. Each winding of transformers 65 and 67 is bridged by a condenser. The winding P of transformers 65 and 67 is bridged by a condenser 71 of .002 mf. capacity. The coil S of transformer 65 is bridged by a condenser 73 of .0001 mf. capacity. The coil S of transformer 67 is bridged by a condenser 75 of .0045 mf. capacity. No condensers are provided at the transformer 69.

In the transformers 65, 67 and 69 the ratio of S turns to P turns is respectively 6½ to 1, 4½ to 1 and 3½ to 1.

In the transformer 69 the S winding is bridged by a variable resistance 77. The resistance element may conveniently comprise a graphite line made by an ordinary lead pencil provided with a movable contact riding along the length of the line, and the fixed contact at one end of the line.

Two air-core transformers 79, 81 are utilized. Air-core transformer 79 has two windings 83, 85, each of 20 turns of No. 30 double-cotton-covered wire. The coil 83 is in series with the P coil of transformer 67, and the other coil 85 is in series with the S coil of transformer 67.

Air-core transformer 81 has two windings 87, 89, each of 45 turns of No. 30 double-cotton-covered wire. Coil 87 is in series with the first coil 53 of the set 15. The other coil 89 is in series with the P coil of transformer 69, and is connected to the plate of the tube 5.

A condenser 91 of .0005 mf. capacity is bridged across coil 87 of transformer 81.

The A-battery A has a potential of 6 volts. The B-battery B has a potential of 22½ volts.

The third battery C has a potential of 60 to 150 volts.

A head set or other translating device T is connected to the positive side of battery C and to the plate of tube 7.

The filament of each tube is connected across the A-battery A. Rheostats 93 may be utilized to carry the intensity of the current in the several filaments.

The negative side of A-battery A is connected to ground 11.

From the positive side of battery B a circuit extends through the P coil of transformer 65, bridged by its condenser 71, thence through the plate coil 55 of set 15 and thence to the plate of tube 1.

From the negative side of battery B a circuit leads through the grid coil 57 of set 15, shunted by its variable condenser 63, thence through the grid resistance 59 shunted by its condenser 61, and thence to the grid of tube 1.

From the negative side of battery A a circuit leads through the S coil of transformer 65, bridged by its condenser 73 thence through the grid coil 25 of set 13, bridged by variable condenser 35, and thence to the grid of tube 3.

From the positive side of battery C a circuit leads to the P coil of transformer 67, bridged by its condenser 71, thence through the coil 83 of transformer 79, thence through the plate coil 21 of set 13, and thence to the plate of tube 3.

A circuit leads from the negative side of battery A through the S coil of transformer 67, bridged by its condenser 75, thence through the coil 85 of transformer 79, thence to the grid of tube 5.

A circuit leads from the positive side of battery C through the P coil of transformer 69, thence through the coil 89 of transformer 81, and thence to the plate of tube 5.

A circuit leads from the negative side of battery A through the S coil of transformer 69, bridged by its variable resistance 77, thence to the grid of tube 7.

A circuit leads from the positive side of battery C through the translating device T and thence to the plate of tube 7.

The coil 87 of transformer 71 is bridged by the condenser 91 and is connected to the coil 53 of set 15.

The operation of the described circuit is as follows:

Incoming signals are impressed on the coil 25 from the aerial 9 by way of the coil 17. The plate coil 21 functions as a reactance coil. Hence the tube 3 may be put into a sensitive condition with regard to the reactance coil and the reactance coil builds up the signal. It may be used to regeneratively stabilize or resonate the circuit.

The radio frequency signal output of the plate of tube 3 is next impressed on the grid of tube 5 by way of the transformer 79.

Tube 5 is an amplifier. The radio frequency output of tube 5 has no practical effect on the sounding device T. Transformer 69 is of the closed core type.

5 However the radio frequency output of tube 5 has affected the transformer 81. Hence the independent circuit of which coil 53 is a part, is energized by radio frequency signals. These signals are reflexed into the 10 described amplifying circuit by way of the reflexing circuit comprising tube 1, coils 55, 57 and battery B. The radio frequency signal in coil 53 is inductively received by coil 57 and fed to the grid of tube 1. At tube 1 the 15 signal is detected and an audio frequency output is obtained from tube 1. This audio frequency output is fed back into the said amplifying circuit by way of the closed-core transformer 65. This said audio frequency 20 output then obviously is amplified in the already described circuit by passing through tube 3, transformer 67, tube 5, transformer 69, tube 7 and into the sounding device T where the signal may be heard as audio frequency. 25 The coil 55 is a reaction coil and is adapted to regeneratively stabilize or resonate the detector circuit.

It will be noted that this is substantially a reflexing regenerative circuit with the tube 30 1 acting as the detector. However the introduction of the transformer 81 between the amplifying detector circuit prevents short circuits of high voltage amplifying circuit batteries from doing damage in the detector 35 circuit.

The audibility and range is enhanced at low cost as the same amplifying circuit handles both audio and radio frequency signals.

In installing the apparatus, and in any required 40 subsequent adjustments, the operator selects the particular tap 19 that is best suited to the other conditions of the circuit.

The extent of cooperation between the fixed and movable coils of each set 13, 15, and therefore 45 the intensity of current induced by said coils is varied by moving the knob 47 rectilinearly in the slot 49 whereas rotation of the same knob serves to tune the apparatus to the desired wave length.

50 After the operator has rotated and shifted the two knobs 47 to produce a suitable intensity of sound in the translating device T, he adjusts the variable resistance 77 until distortion of the sound waves produced by the 55 translating device T is reduced or eliminated.

In the subsequent operation of the apparatus, further adjustment of the resistance 77 may be required in order to improve the 60 results obtained in listening to different stations, but further adjustment of the taps 19 is ordinarily not required.

The number of tubes may be varied, in order to secure stages of amplification other than the one herein shown by way of illustration. When some other number of tubes is

employed than four, then the circuits need to be appropriately altered.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense.

I claim:

1. In a radio system, a dual tuning control comprising a rotary variable condenser, a stationary inductance, a hinged inductance in variable inductive relation with said stationary inductance, a vertical panel on which said condenser is mounted, vertical guides on said panel which permit the condenser to be integrally moved therein, a cord secured to the frame of said condenser and to the hinged inductance, a spring affixed between and to said inductances said spring pulling said inductances together as the condenser is moved upwardly and tending to counterbalance the weight of the condenser as said condenser is moved downwardly, the varying of the capacity of said condenser being controlled independently of its vertical movement.

2. In a radio system, a dual tuning control comprising a rotary variable condenser, a stationary secondary inductance, said condenser shunting said inductance, a hinged plate inductance in variable inductive relation with said secondary inductance, a vertical panel on which said condenser is mounted, vertical guides on said panel which permit the condenser to be integrally moved therein, a cord secured to the frame of said condenser and to the hinged inductance, a spring affixed between and to said inductances, said spring pulling said inductances together as the condenser is moved upwardly and tending to counterbalance the weight of the condenser as said condenser is moved downwardly, the varying of the capacity of said condenser being controlled independently of its vertical movement.

In testimony whereof, I have signed my name to this specification this 20th day of March, 1924.

LLOYD Q. SLOCUMB.
